CLAIM

The ornamental design for an eye glass frame, as shown and described.

DESCRIPTION

FIG. 1 is a perspective view of an eye glass frame showing my new design;

FIG. 2 is a top plan view thereof;

FIG. 3 is a front elevational view thereof;

FIG. 4 is a left side elevational view thereof, it being understood that a right side elevational view is a mirror image thereof;

FIG. 5 is a rear elevational view thereof; and,

FIG. 6 is a bottom plan view thereof.

Any portion of any figure shown in broken lines is for environmental purposes only and forms no part of the claimed design.
